his Attorney.

UNITED STATES PATENT OFFICE.

MARIUS JEAN-BAPTISTE BARBAROU, OF PARIS, FRANCE.

CONTROL OF CARBURETORS.

Application filed February 23, 1924, Serial No. 694,804, and in France March 24, 1923.

When an engine is intended to work at high altitudes, which is particularly the case for aviation engines, it is desirable to increase the ratio of volumetric compression 5 of the engine at high altitudes, so as to have an engine which is still powerful at these altitudes. But under these conditions, if the engines were operated on the ground upon full gas admission, this would result 10 in an abnormal strain on the engine; it is thus required to reduce the volume of gas admitted into the cylinders at low altitudes, and in order that the pilot or the driver shall not forget to reduce this volume, it is preferable to use an automatic device.

The present invention has for its object a device for the control of the throttle valve of the carburetor or carburetors of an internal combustion engine and in particular of 20 aviation engines, one feature whereof resides in that it comprises an elastic diaphragm or like member, one face whereof is subjected to a pressure substantially equal to the atmospheric pressure at the lowest 25 altitude at which the engine is intended to work, while its other face is subjected to the surrounding atmospheric pressure, means being provided for operatively connecting said diaphragm to the transmission gear 30 and whereby a further movement is imparted to said transmission gear according to the altitude and the opening of the throttle valve of the carburetor, or of each carburetor, increases with the altitude.

35 By the use of this device the engine may give its whole power at high altitudes, and there is no risk, at low altitudes, of damaging the engine since the maximum possible opening of the carburetor throttle will be 40 reduced in an automatic manner.

Other features of the invention will be set forth in the following description.

In the appended drawing given by way of example

45 Fig. 1 shows diagrammatically a construction of the control device according to the invention.

Fig. 2 is a section on a larger scale, on the line A—A (Fig. 3) of a detail.

Fig. 3 is a section on the line B—B (Fig. 50 2).

In the construction shown in Fig. 1, 1 is the throttle of the carburetor 2, and which is mounted on a spindle 3 secured to an arm 4 connected by a link 5 with the end of a 55 swinging lever 6 movable on the spindle 7. This spindle 7 provides for the simultaneous control of several carburetors, which is necessary since aviation engines are usually provided with two carburetors. To this end, 60 an arm parallel to the lever 6 and actuating, by a link analogous to the link 5, the throttle of the other carburetor, is mounted on the spindle 7.

At the other end of the lever 6, or at the 65 end of another arm secured to the spindle 7, is mounted a link 8 which carries at its other end a roller 9 engaged in the guide slot 10 of a sector shaped lever 11, movable on the shaft 12 and actuated by the pilot 70 by means of the rod, or rod and link gear 13.

To the link 8 is attached a rod 14 which is secured on the other hand to a membrane or elastic diaphragm 15 forming the bottom 75 of a hermetically closed chamber 16 in which prevails the atmospheric pressure on the ground or a pressure somewhat higher. The membrane 15 is constantly urged by a spring 17 which tends to bring it towards the 80 top, consequently with the link 8.

The operation of the device is as follows:

On the ground or at a low altitude, the pressure in the chamber 16 and the force 85 of the spring 17 are such that the link 8 is raised and has the position shown in full and dotted lines at 8^a. In these conditions, the pilot acting on the rod and link gear 13 in order to move the throttle 1 of the carburetor 2, can only, for a given stroke of oscillation of the lever 11 on its spindle 12, impart a small oscillation to the shaft 7 and hence obtain a small opening for the throttle 1.

But when the engine rises in the air the surrounding atmospheric pressure will diminish, and the pressure in the chamber 16

thus preponderates and is exercised on the diaphragm 15, compressing the spring 17 and lowering the roller of the link 8 in the slot of the lever 11. It results therefrom 5 that, for a given angle of oscillation of this lever 11 on the spindle 12 under the action of the rod and link gear 13, the shaft 7 will turn through a greater angle than what it turned through when the link 8 was in the 10 position 8^a, so that the throttle 1 will open further. The throttle can be open to the maximum only when the altitude reached is such that the link 8 is lowered into the position 8^b.

15 One will observe that if the lever 11 is disposed so that in the position of Fig. 1 the centre of the circle of the slot 10 is located at the point where the link 8 is attached to the lever 6, whatever may be the 20 movements imparted by the manometric chamber to the link 8, no action will be felt on the throttle of the carburetor. One can adjust the controls so that this position of the lever 11 corresponds to the position of the 25 throttle for the slow speed of the engine.

Obviously the construction of the transmission gear, comprising the curved lever 11 and the rod 8 shown in Figs. 2 and 3, is given solely by way of example, and it 30 might be replaced by any other device producing the same effect, that is to say admitting the modification of the maximum opening of the carburetor according to the altitude at which the engine is working.

35 Having now described my invention what I claim as new and desire to secure by Letters Patent is:

1. A transmission gear for the control of the carburetor of an internal combustion 40 engine comprising a control member, a rod and link gear operatively connecting said control member with the throttle valve of the carburetor, an elastic membrane one face whereof is subjected to a pressure substantially equal to the atmospheric pressure at the lowest altitude at which the engine is intended to work, while its other face is subjected to the surrounding atmospheric pressure and means for operatively connecting said membrane to one rod of said rod and link gear, said rod being adapted to slide on the preceding link whereby the operative length of said link may be varied and the ratio of the transmission of movement is 45 varied in accordance with the altitude and increases at the same time as the latter.

2. A transmission gear for the control of the carburetor of an internal combustion engine comprising a control member, a sector-shaped slide member pivoted at one end and operatively connected at its other end with said control member, a rod one end whereof is adapted to slide on said slide member, means for operatively connecting said rod 50 to the throttle valve of the carburetor, an

elastic membrane one face whereof is subjected to a pressure substantially equal to the atmospheric pressure at the lowest altitude at which the engine is intended to work, while its other face is subjected to the surrounding atmospheric pressure and means for operatively connecting said membrane to said rod. 70

3. A transmission gear for the control of the carburetor of an internal combustion 75 engine comprising a control member, a sector-shaped slide member pivoted at one end and operatively connected at its other end with said control member, a rod one end whereof is adapted to slide on said slide member, a rod and link gear operatively connecting the other end of said rod to the throttle valve of the carburetor, the centre of said sector-shaped slide member coinciding with said other end of said rod when the latter is in its mean angular position, an elastic membrane one face whereof is subjected to a pressure substantially equal to the atmospheric pressure at the lowest altitude at which the engine is intended to work, while its other face is subjected to the surrounding atmospheric pressure and means for operatively connecting said membrane to said rod. 80

4. A control gear for the carburetor of an 85 internal combustion engine comprising in combination a control member operated by the operator, a rod and link gear operatively connecting said control member to the carburetor throttle, an elastic membrane subjected on one face to a predetermined constant pressure and on the other face to the surrounding atmospheric pressure, and means operatively connecting said membrane with one link of said gear and whereby the angular position of said link is varied in accordance with the altitude at which the engine is working. 90

5. A control gear for the carburetor of an 95 internal combustion engine comprising in combination a control member operated by the operator, a rod and link gear operatively connecting said control member to the carburetor throttle, a tight receptacle one wall whereof is constituted by an elastic membrane the outer face whereof is subjected to the surrounding atmospheric pressure, a predetermined constant pressure prevailing in said receptacle, a spring acting upon said membrane in opposition to said constant pressure, and means operatively connecting said membrane with one link of said gear and whereby the angular position of said link is varied in accordance with the altitude at which the engine is working. 105

6. A control gear for the carburetor of an 110 internal combustion engine comprising a control member operated by the operator, a rod and link gear embodying two swinging arms respectively connected to said control 115

member and to the carburetor throttle, an intermediate member upon which said arms are jointed, and an elastic membrane subjected on one face to a predetermined constant pressure and on the other face to the surrounding atmospheric pressure, and means for operatively connecting said intermediate member to said elastic membrane and whereby the angular position of said arm connected to the carburetor throttle is varied in accordance with the altitude at which the engine is working.

In testimony whereof I have signed my name to this specification.

MARIUS JEAN-BAPTISTE BARBAROU.
